United States Patent

Des. 238,408

Patented Jan. 13, 1976

238,408

NAPKIN DISPENSER

Adam Pecht, Cudahy, Calif.
(11924 Gurley Ave., Downey, Calif. 90242)

Filed Feb. 19, 1974, Ser. No. 443,914

Term of patent 14 years

Int. Cl. D7—06

U.S. Cl. D7—72

FIG. 3

FIG. 4

FIG. 1

FIG. 2

FIG. 1 is a top front perspective view of a napkin dispenser showing my new design;

FIG. 2 is an elevational view of the side opposite that shown in FIG. 1;

FIG. 3 is a bottom plan view thereof; and

FIG. 4 is an end elevational view as seen from the left of FIG. 2.

I claim:

The ornamental design for a napkin dispenser, as shown.
